(57) **CLAIM**

The ornamental design for a plaster for tracheostoma, as shown and described.

DESCRIPTION

FIG. 1 is a perspective front view of a plaster for tracheostoma showing our new design;

FIG. 2 is a front elevation view thereof;

FIG. 3 is a rear elevation view thereof;

FIG. 4 is an end elevation view thereof;

FIG. 5 is an opposite end elevation view thereof;

FIG. 6 is a side elevation view thereof; and,

FIG. 7 is an opposite side elevation view.

The broken line showing of parts of the drawings is included for the purpose of illustrating use and environment and forms no part of the claimed design.

The design relates to a plaster device for persons having a tracheostoma comprising a disc having a socket for attaching a tracheostoma valve, the disc having a central opening and a rear side with adhesive tape, the disc being fixed to the tape.
